FIG. 1 is a perspective view of a combined holder and dispenser showing my new design, wherein the invention lies in a combined toothbrush holder and toothpaste dispenser;

FIG. 2 is a front elevational view thereof;

FIG. 3 is a rear elevational view thereof;

FIG. 4 is an elevational view taken from one side thereof;

FIG. 5 is an elevational view taken from the side opposite that shown in FIG. 4;

FIG. 6 is a top plan view thereof;

FIG. 7 is a bottom plan view thereof;

FIG. 8 is a perspective view of a modified form of the combined holder and dispenser shown in FIG. 1 wherein the design lies in a combined toothbrush holder, toothpaste dispenser and cup dispenser;

FIG. 9 is a front elevational view of FIG. 8;

FIG. 10 is a rear elevational view of FIG. 8;

FIG. 11 is an elevational view taken from one side of FIG. 8;

FIG. 12 is an elevational view taken from the side opposite that shown in FIG. 11;

FIG. 13 is a top plan view of FIG. 8; and FIG. 14 is a bottom plan view of FIG. 8.

The broken line representation of part of a toothbrush and a toothpaste tube in FIGS. 2, 5 and 9 and part of a cup in FIG. 9 is for purposes of illustration only.

I claim:

The ornamental design for a combined holder and dispenser, substantially as shown and described.
